UNITED STATES PATENT OFFICE.

WILLIAM M. EVANS, OF KEARNEY, NEBRASKA.

BUMPING-POST.

1,132,315.

Specification of Letters Patent. Patented Mar. 16, 1915.

Application filed July 8, 1914. Serial No. 849,763.

To all whom it may concern:

Be it known that I, WILLIAM M. EVANS, a citizen of the United States, residing at Kearney, in the county of Buffalo and State 5 of Nebraska, have invented new and useful Improvements in Bumping-Posts, of which the following is a specification.

The invention relates to bumping posts, and has for its primary object to provide a 10 post wherein the impact jar between it and a railway car will be absorbed so as to avoid any damage to either the post or the car.

Another object of the invention is the provision of a bumping post wherein the frame 15 structure is materially strengthened and the post will absorb the jar when a railway car strikes the same, the frame structure and the post being of novel form to assure durability and strength thereto.

20 A further object of the invention is the provision of a bumping post of this character which is simple in construction, thoroughly reliable and efficient in its operation, and inexpensive in manufacture.

25 With these and other objects in view, the invention consists in the construction, combination and arrangement of parts as will be hereinafter fully described, illustrated in the accompanying drawings, and pointed 30 out in the claim hereunto appended.

In the drawings:—Figure 1 is a side elevation of a bumping post constructed in accordance with the invention. Fig. 2 is a top plan view thereof. Fig. 3 is an end elevation. Fig. 4 is an opposite end elevation. Fig. 5 is a vertical longitudinal sectional view through the same. Fig. 6 is a vertical 35 transverse sectional view thereof.

Similar reference characters indicate corresponding parts throughout the several 40 views in the drawings.

Referring to the drawings in detail, the bumping post comprises a frame, the base sills 5, cross pieces 6 connected thereto, intermediate and outer uprights 7 and 8 respectively, and the plates 9, constituting the frame, the uprights being secured in vertical position in any suitable manner, while the plates 9 are bolted or otherwise fastened 45 thereto. Bolted or otherwise secured to the base sills 5 and to the rearmost uprights 9 are rearwardly inclined brace beams 10, while engaged in the uprights 9 at their upper ends are tie rods 11, and also passed 50

through the said uprights are forwardly inclined brace rods 12 which together with the tie rods serve to hold the uprights in rigid position.

Slidably mounted in the front plate 9 is a plurality of plungers 13, to the front ends 60 of which is fixed a buffer head or post 14, each of the plungers being formed near their front ends with shoulders 15 against which rests coiled resistance springs 16, which latter work against the front plate 9, these 65 springs being coiled about the plungers 13 and serve to absorb jars against the buffer post 14 when a railway car strikes the same. The intermediate plunger 13 is formed with a shoulder 17 spaced from its rear end, and surrounding said plunger is a coiled expansion spring 18 which works against the shoulder 17 at one of its ends, while its opposite end is spaced from the rearmost plate 9, the spring 18 being of less resistance quality than any one of the springs 16. Likewise 75 the outer plungers 13 have formed spaced from their rear ends shoulders 19, and surrounding the said plungers are coiled resistance springs 20 which bear against the 80 shoulders 19 at their forward ends, while their opposite ends are spaced from an abutment post 21 and a cross brace 22 respectively, these springs 20 being of less resistance quality than the springs 16 so that on 85 the initial movement of the buffer 14 the springs 16 will resist the impact, and thereafter the springs 18 and 20 will come into action to assist in resisting the impact so as to absorb the jar when the railway car 90 strikes the buffer to avoid damage to the said car or the bumping post. The intermediate plunger 13 is also trained through the abutment post 21, and the rear plate 9 and the outer plungers 13 are also trained 95 through the abutment post 21 and the cross brace 22 respectively so that they will be properly guided during displacement of the buffer 14 when struck by a car.

From the foregoing it is thought that the 100 construction and manner of use of the device will be clearly understood, and therefore a more extended explanation has been omitted.

What is claimed is:—

A bumping post comprising a frame, slideable plungers mounted in the said frame, a buffer head carried by the plungers, and a

plurality of resistance springs arranged in series about the plungers and working against the same for absorbing shocks incident to the displacement of the buffer head, one series of resistance springs being of greater resistance quality than the other series of springs.

In testimony whereof I affix my signature in presence of two witnesses.

WILLIAM M. EVANS.
